UNITED STATES PATENT OFFICE.

WILLIAM J. H. STRONG, OF CHICAGO, ILLINOIS.

DESIGN FOR A SUPPORT OR STAND.

52,255.

Specification for Design.

Patented Aug. 6, 1918.

Application filed May 21, 1917. Serial No. 170,066. Term of patent 14 years.

To all whom it may concern:

Be it known that I, WILLIAM J. H. STRONG, citizen of the United States, residing at Chicago, in the county of Cook and State of Illinois, have invented a new, original, and ornamental Design for a Support or Stand, of which the following is a specification, reference being had to the accompanying drawing, forming a part thereof.

The figure is a perspective view of a support or stand, showing my new design.

I claim:—

The ornamental design for a support or stand as shown.

WILLIAM J. H. STRONG.

Witness:

E. F. WILSON.
